DESIGN FOR A BOX FOR TOILET ARTICLE

Christian J. Groos, Bronxville, N. Y., assignor to Boonton Molding Company, Boonton, N. J., a corporation of New Jersey

Application January 3, 1938, Serial No. 74,057

Term of patent 14 years

To all whom it may concern:

Be it known that I, Christian J. Groos, a citizen of the United States, and a resident of Bronxville, county of Westchester, and State of New York, have invented a new, original, and ornamental Design for a Box for Toilet Article, of which the following is a specification, reference being had to the accompanying drawing forming a part thereof, wherein:

Fig. 1 is a perspective view showing a box for toilet article embodying my new design; and

Fig. 2 is a plan view of the same.

The relief ornamentation on the exterior of the toilet box is the characteristic feature of my design.

I claim:

The ornamental design for a box for toilet article, substantially as shown and described.

CHRISTIAN J. GROOS.
